PAPER BORING AND SLOTTING MACHINE

Mark J. Garlick, Chicago, Ill., assignor to The Challenge Machinery Company, Grand Haven, Mich., a corporation of Michigan

Application July 11, 1938, Serial No. 218,552

5 Claims. (Cl. 164—86)

This invention relates to a paper drilling and slotting machine, for the simultaneous drilling of holes through paper and with the slotting or slitting of the paper outward from the holes drilled to an adjacent edge thereof, said slots thereby produced being of different forms, and which are produced in their different forms by means of different interchangeable cutters, or by rearranging and changing the position of the cutting blades whereby substantially any of the well-known and accepted types of slots or notches cut in the edges of the paper may be produced. There has heretofore been issued a patent having No. 2,029,624, relating to an attachment for paper drilling machines by means of which slots having parallel sides may be produced leading from the holes which have been drilled to the edges of the paper. In our invention where the paper is to be drilled and slotted, the operation of drilling and slotting takes place simultaneously without the necessity generally of performing one operation after the other as in the above patent.

It is a primary object and purpose of the present invention to provide a very practical and useful means for obtaining the simultaneous drilling and slotting of the paper which can be attached to drilling machines of the character shown, for example in said patent to which reference is made, or used with the structure shown in the United States Patent No. 2,173,817, issued September 26, 1939. A further object of the invention is to provide a machine of this character with a practical and serviceable means for removing the small pieces of paper cut from the paper sheets when any slotting thereof is performed, getting them immediately out of the way and thereby preventing any interference with the operations of the machine.

An understanding of the invention and the construction which embodies the same may be had from the following description, taken in connection with the accompanying drawings, in which:

Fig. 1 is a partial vertical section and side elevation of the machine equipped with our invention, the section being from front to rear of the machine and substantially on the plane of line 1—1 of Fig. 2, looking in the direction indicated by the arrows.

Fig. 2 is a fragmentary vertical section substantially at right angles to that shown in Fig. 1.

Fig. 3 is a fragmentary plan view of the table and the back and end gauges of the machine.

Fig. 4 is a somewhat enlarged fragmentary vertical section at the front central portion of

the machine showing the paper drill and the cutters for the slots in side elevation.

Fig. 5 is a horizontal section substantially on the plane of line 5—5 of Fig. 4.

Fig. 6 is a somewhat enlarged perspective view of one of the slot cutting attachments which may be used with the machine.

Fig. 7 is an underplan view thereof.

Fig. 8 is a similar underplan view showing the cutters adjusted to a different position with respect to each other.

Fig. 9 is a perspective view of a slitting cutter.

Figs. 10 and 11 are underplan views showing said slitting cutters with the cutter knives in different positions.

Fig. 12 is an underplan view of a still further form of cutter for cutting what is known as the Kalamazoo notch or slot in paper.

Fig. 13 is a central vertical section therethrough.

Fig. 14 is a fragmentary plan showing the drilling hole and communicating slot cut in the paper with the cutters in the position as shown in Fig. 7.

Fig. 15 is a similar view with the cutters adjusted as in Fig. 8.

Fig. 16 is a similar view showing the hole drilled and a slot to one side of the diameter of such hole and as produced with a slitting attachment as shown in Fig. 9, with the cutter adjusted to one side.

Fig. 17 is a view similar to Fig. 16 wherein the slot has been completed by a second slit spaced from and parallel to the first one, that is, with the cutter adjusted to the opposite side, the two positions of the cutters being shown in Figs. 10 and 11, and

Fig. 18 is a fragmentary plan of an edge portion of a paper sheet with a Kalamazoo notch such as is produced by the cutter shown in Fig. 12.

Like reference characters refer to like parts in the different figures of the drawings.

The paper drilling machine with which this invention is concerned is similar in many respects to structure shown in the previously recited patents.

A lower supporting and covered housing 1 has above it an immediate table support 2 on which a horizontal table 3 is mounted, it having a recess in which a wooden plug 4 is inserted to come directly below the lower ends of the drill and the slotting cutters. The sheets of paper, in a pack 5 of superimposed sheets, are located upon the upper side of the table 3 with the edge portions thereof which are to be drilled and cut located over the block 4.

A head 6 for carrying the drill, cutters and the motor for driving the drill is adjustably supported on two spaced apart vertical posts 7 which are normally lifted to an upper position by compression springs 8. Such posts 7 may be pulled in a downward direction by a foot pedal 9 through a link connection at 10 whereby on downward pressure upon the pedal 9 the post 7 and the drill and cutters carried thereby will be moved in a downward direction. For purposes of illustration, the simple foot pedal method of moving the drill and cutters in a downward direction are shown, but it is to be understood that the power operated means shown in the United States Patent No. 2,173,817, issued September 26, 1939, for moving the drill in a downward direction will preferably be used when simultaneous drilling and cutting of the slots occurs. Insofar as the present invention is concerned, any means, whether a power means or one which is operated directly by the weight of the operator on a foot pedal such as that indicated at 9 may be used, it being requisite only that a sufficient force be provided for the drill and cutter knives to pass through the paper pack.

As in the previous patents and applications referred to, the drill is driven by an electric motor 11 carried at one end of the head 6 which, through an interposed endless belt 12, drives a vertical drill spindle 13 at the lower end of which (Fig. 4) is a drill receiving chuck 14. The hollow paper drill 15, such as shown in United States Patent No. 2,141,712, has a shank at its upper end adapted to be received in said chuck 14. The usual spring actuated presser foot 16 carried by vertically reciprocable rods 17 and yieldingly moved in a downward direction by coiled springs 18, the rods being mounted for up and down movement on a fixture 19 located at the forward portion of the head 6 is used the same as before, to exert a pressure upon the pack 5 to hold the paper sheets while the drilling and cutting operations are being performed, and permit the drill and cutters to move downwardly while the presser foot 16 stays in a fixed position against the uppermost sheet of the paper pack.

The pack 5 of paper sheets is located at its inner or rear edge against a back gauge consisting of two aligned sections 20 (Fig. 3), the adjacent ends of which are spaced a short distance apart and, through right angle positioned brackets 21, connect with a short central section 22 located a distance back of the sections 20 of the gauge. There is, therefore, left back of the rear edges of the pack 5 an opening or space 23, as shown in Fig. 3. An end gauge 24 which may be adjusted to different selected positions on the back gauge through the use of the different length rods 25, comes against one of the edges of the pack 5. It is not necessary to describe this end gauge and the method of operation in detail as it is fully disclosed in Patent No. 1,928,383, issued September 26, 1933. It is enough to say that the pack 5 of paper sheets is held in proper position with reference to the drill by engaging against the back gauge at its rear edge and at the end gauge at one side edge, and that the sheet pack may be moved to different positions with respect to the back gauge through the different selected positions with respect to the back gauge through the different selected positions which may be set for end gauge 24, as fully described in said Patent No. 1,928,383. The open space at 23 is immediately back of the wood block 4 and the drill and cutters as hereafter described are moved down-

wardly to and in engagement with the paper sheets 5 and through them in front of and partly within the front portion of the space at 23 and drill and cut openings and communicating slots 5 in the paper at several predetermined and selected points in the length of the rear edge of the pack 5 of paper sheets.

A circular opening is made through the table 3 immediately below the rear portion of said open space 23. A vertical tube 26 (Figs. 1 and 2) is inserted at its upper end in said opening, extends through the upper side of the housing 4, communicating with a fan housing 27, the upper end portion of which is enlarged and has an electric motor 28 therein on the shaft of which is a suction fan 29. This is for the purpose of drawing the paper which is severed from the sheets of paper when the slots are cut through a suction draft of air which moves downwardly through the tube 26 and is expelled together with the paper parts carried in the current of air at the end of the housing 27.

A supporting casting 30 (Figs. 1 and 4) is bolted 25 to the underside of the head 6 at the front end of which the fixture 19 previously described is adjustably supported. At the front portion and at the under side of the supporting casting 30 a block 31 is adjustably mounted having a circular 30 opening 32 therethrough, larger in diameter than the diameter of the chuck 14, the drill 15 extending through said opening. The block 31 has slotted wings 33 at its side through which set screws 34 pass, threading upwardly into the casting 30 and permitting a range of forward and back adjustment. The block 31 has vertical guide slots 35 (Fig. 5) at its rear side, in which the upper ends of several interchangeable cutter assemblies may be adjustably guided in a vertical 40 direction.

The cutter assembly includes a supporting body 36, vertically slotted between its edges at 37, and through which set screws 38 pass and thread into the block 31, guide ribs 39 extending through guide grooves 35 as shown in Fig. 5.

The lower end portion of the block 36 is milled centrally to make an opening or recess having angularly positioned sides, one at the inner side of each of the integral projections 40 at the lower end portion of the said block 36. In the open space provided, and indicated at 41, cutters having bodies 42 are adapted to be positioned and clamped in place against the inclined sides of the opening at 41 by screws which pass through the parts 40 through openings in the bodies of the cutter 42 and through shims 43 and 44. In one position, as shown in Figs. 6 and 7, said shims 43 and 44 are at opposite sides of the bodies 42 of the cutters. In another position, that shown in Fig. 8, the bodies 42 of the cutters are brought against the inner sides of the parts 40 and both shims 43 and 44 are at the outer sides thereof. The immediate cutter portions 45 sharpened at their lower edges extend forwardly from the supporting member 36, coming in close proximity at their front edges to the drill 15 (Figs. 1, 7 and 8). The distance between the cutters and drill is very small and may be in the order of .001 inch so that the slot cut by the cutter substantially joins the hole cut by the drill. As shown in Fig. 4, the lower cutting edges of the parts 45 lie in substantially the same horizontal plane with the lower end of the hollow paper drill 15.

It is evident that with the downward movement 75 of the posts 7 and the accompanying downward

movement of all the parts carried thereby, the drill and the cutters 45 move together in a downward direction simultaneously drilling and slotting the paper sheets. In Fig. 14 the circular hole drilled by the drill is shown at 46 and the substantially V-shaped slot 47 cut between cutters, when they are located more closely together, as in Fig. 7, is shown at 41. In Fig. 15 the drilled hole 46 is the same as before but the slot 41a has its diverging sides more widely separated than in Fig. 14.

In Fig. 9 the holder 36a for the cutter has the same vertical slot 37 for passage of the clamping screws 38 and the same ribs 39 to enter the guiding grooves at 35. The lower portion of the member 36a is vertically slotted for the reception of a cutter body 48 having a projecting immediate cutter portion 49 and two shims 50. In Fig. 10 the cutter is shown at one side of the slot with the shims 50 between it and the opposite side. In Fig. 11 the cutter is shown at said opposite side with the two shims at the other side thereof. With the downward movement of the drill and the accompanying cutter, the lower edge portion of the section 49 being sharpened, a hole 46 will be drilled and a slit 51 made in the paper as shown in Fig. 16. Such slit is to one side of a diameter of the hole 46 which parallels said slit. In a second operation the drill will be removed and the cutter alone operated, whereupon a second slit will be cut through the paper spaced from but parallel to the first slit 51, thereby leaving a slot 52 having parallel sides as shown in Fig. 17. If the cutter is located between the two shims 50, a single centrally located slit may be made.

A third form of cutter assembly may be used with the machine for cutting what is known as the Kalamazoo slots or recesses in the edges of the paper at spaced apart points. This includes a supporting body 36b, similarly slotted at 37 for the attachment by means of the set screws 38 and having a cutter 53, of the shape best shown in Fig. 12, connected with the supporting body and with its lower edges sharpened and of a shape to make a substantially rectangular slot or recess 54 (Fig. 18) when the cutter is moved down to pass through the sheets of the pack 5. In this case the drill will not be used. The lower portion of the body 36b is recessed and a curved member 55 secured in the upper portion thereof, as shown at Fig. 13, the front edge of which comes to the rear inner cutting edge of the cutter 53, said member 55 serving as a deflecting member for the paper parts which are cut from the sheets and acting to move the same automatically in a rearward direction and direct them into the descending current of air passing through the tube 26 and thence to and through the fan housing 27.

A horizontal plate 56 is mounted for a sliding movement upon a guideway 57 in the upper part of the supporting casting 2 at one position, as shown in Fig. 2, passing through a side of and across the tube 26. When in such position across the tube an insurance is had against the passage of any articles downwardly through the tube to the fan 29, such as tools or the like which may be around the machine when used in various adjustments of the machine or in interchanging the slotting assemblies. A vertical leg 58 is integral with and extends downwardly from the slide support 57 at the lower end of which an arm 59 is pivotally mounted and extends upwardly (Fig. 1), carrying a roller 59a at its upper end to pass through a slot in the plate 56 whereby when the arm swings about its pivot the slide is moved

horizontally. The arm 59 is fixed to a pivot pin 60 which, on the opposite side of the vertical support 58, carries a short substantially horizontal arm 61 on which a relatively heavy weight 62 of the form best shown in Fig. 2 is pivotally mounted, as at 63. The weight 62 is vertically slotted with a slot 64. A rod 65 connected with one of the posts 7 extends horizontally into the slot 64 at its end. On the upward movement of the post 7, under the influence of the springs 8, rod 65 engaging against the weight 62 at the upper end of slot 64 lifts the weight to the position shown in Fig. 2, turning the arm 59 in a clockwise direction and thereby moving the plate 56 into and across the tube 26 to the position shown in Fig. 2. On the downward movement of the post 7 when the drill and cutters are moved toward the sheet pack 5, rod 65 moves downwardly and the weight 62 follows it, so that by the time the drill and cutters have reached the uppermost sheet of paper in the pack 5, the plate 56 has been moved so as to clear the tube 26. The tube is then open for the downward passage of the pieces of paper which are cut from the sheets of paper when the slotting takes place. But automatically on the return upward movement of the drill to an upper position, the plate 56 is carried across the upper end portion of the tube 26; and it is moved to its outer position to clear the tube only at the times when the drilling and cutting operations take place. This structure is a safeguard and insurance against the dropping of undesired articles through the tube to the rotating fan 29 which, if it occurred, might damage the fan or the motor 28 and which also might be hard to recover. But if anything drops down the tube only to the stop which is made by the plate 56, it is relatively easy to recover the same and without any danger of damage. A further object is to conserve power since the fan is driven more easily when air is prevented from entering the tube.

The construction described has proven very practical and useful. The packs of paper, each pack including a plurality of sheets of paper in superimposed relation, are very quickly and accurately processed and provided with the desired shape or configuration of slot therein, most of which include an inner portion of circular form made by the drill, with lateral slots leading from the circular openings to the adjacent edge of the sheets of paper. The various slotting devices consisting of the supports 36, 36a or 36b and the appropriate cutters secured thereto are interchangeable. The adjustment of the supporting block by means of the set screws 34 and the slots through which they pass, permits the accurate adjustment of the cutters to desired positions with reference to the drill.

The invention is defined in the appended claims and is to be considered comprehensive of all forms of structure coming within their scope.

I claim:

1. In a machine for forming notched openings in a stack of sheets and the like, a boring tool, and a slotting tool located closely adjacent said boring tool, said slotting tool comprising a blade angular in cross section and having the work engaging edge thereof sharpened, said sharpened edge being substantially coplanar with the cutting edge of the boring tool, and means for reciprocating said tools together relative to the work.

2. In a machine of the class described, the com-

combination of a hollow rotatable punch, a slotting cutter having spaced cutting edges disposed radially of said punch and with its tip closely adjacent to but spaced from said punch so that the periphery of the punch is not in rotating contact with the cutter, and means for simultaneously feeding said punch and cutter to the work.

3. In a machine of the class described, the combination with a work table and a carriage associated for relative reciprocating movement of a tubular boring tool on said carriage and a slotting cutter mounted on said carriage in radial relation to said boring tool with its tip closely adjacent to the boring tool and having a cutting edge in approximately the plane of the cutting edge of the boring tool.

4. In a machine for forming notched apertures in a stack of paper sheets, the combination with a work table and a carriage associated for relative reciprocating movement, of a rotary

tubular boring tool on said carriage and adapted to form an aperture through the stack, and a slotting cutter adapted to form a notch in the edge of the stack and mounted on said carriage

5. In a machine of the class described, the combination in radial relation to said boring tool with its tip spaced from the boring tool a distance sufficiently small to permit ready tearing of the material of the stack between the aperture and notch.

6. In a machine of the class described, the combination of a rotary tubular boring tool adapted to form an aperture through the stack, a slotting cutter adapted to form a notch in the stack and mounted in radial relation to said boring tool and with its tip spaced from the boring tool

10 a distance sufficiently small to permit ready tearing of the material of the stack between the aperture and notch, and means for simultaneously actuating said boring tool and cutter.

MARK J. GARLICK.
